FOREIGN PATENT DOCUMENTSCN 2617039 Y 5/2004
(Continued)**OTHER PUBLICATIONS**

Notification of the First Office Action from Chinese Patent Application No. 201010167346.2. dated Feb. 29, 2012.

(Continued)

Primary Examiner — Marcus Jackson(74) *Attorney, Agent, or Firm* — Koppel, Patrick, Heybl & Philpott**(57) CLAIM**

The ornamental design for an LED package, as shown and described.

DESCRIPTION

FIG. 1 is a perspective view of one embodiment of an LED package showing my design;

FIG. 2 is a top plan view of the LED package shown in FIG. 1;

FIG. 3 is a bottom plan view of the LED package shown in FIG. 1; and,

FIG. 4 is a front elevation view of the LED package shown in FIG. 1, with the back and both side elevation views being substantially similar.

The broken lines in any of FIGS. 1-4 are for illustrative purposes only and form no part of the claimed design.

- Declaration of Charles Swoboda under 37 C.F.R. § 1.132, dated: Aug. 19, 2009.
- Nichia Corp. White LED Part No. NSPW300BS, Specification for Nichia White LED, Model NSPW300BS., Jan. 14, 2004.
- Nichia Corp., White LED Part No. NSPW312BS, Specification for Nichia White LED, Model NSPW312BS. Jan. 14, 2004.
- Kim J. K et al. "Strongly Enhanced Phosphor Efficiency in GaInN White Light-Emitting Diodes Using Remote Phosphor Configuration and Diffuse Reflector Cup" Japanese Journal of Applied Physics, Japan Society of Applied Physics, Tokyo, JP, vol. 44, No. 20-23, Jan. 1, 2005 XP-001236966, pp. 649-651.
- Office Action from Application No. 29/294,459, dated: Apr. 2, 2010.
- Response to Office Action, Application No. 29/294,459, dated: May 3, 2010.
- Office Action from Application No. 11/149,998, dated: May 18, 2010.
- Office Action from Application No. 12/321,059, dated: May 17, 2010.
- Office Action from Application No. 12/069,827, dated: Apr. 20, 2010.
- Office Action from Application No. 12/152,766, dated: Mar. 12, 2010.
- Response to Office Action, Application No. 12/154,691, dated: May 17, 2010.
- Office Action from Application No. 11/149,998, dated: Nov. 20, 2009.
- Notice of Allowance for Application No. 29/294,459, dated: Aug. 31, 2010.
- First Office Action for Chinese Patent Application No. 200780019643.9 dated Mar. 29, 2010.
- Notice of Reasons for Rejection for Japanese Patent Application No. 2007-211901 dated Apr. 14, 2011.
- International Preliminary Report on Patentability for PCT/CN2010/070073 mailed Apr. 28, 2011.
- International Search Report and Written Opinion for PCT/CN2010/001865 mailed Jun. 9, 2011.
- Notice of Reasons for Rejection for Japanese Patent Application No. JP 2008-51569 dated May 19, 2011.
- Notice of Reasons for Rejection for Japanese Patent Application No. JP 2009-507195 dated Jun. 10, 2011.
- Office Action from related China Application No. 200710142310.7, dated: Dec. 11, 2009.
- First Office Action for Chinese Patent Application No. CN 200710152109.7 issued Jul. 29, 2011.
- Extended Supplementary European Search Report for European Application No. EP 07789665.2 dated Nov. 7, 2011.
- Second Office Action for Chinese Patent Application No. CN200880009255.7 mailed Oct. 13, 2011.
- International Search Report and Written Opinion for PCT Application No. PCT/US2011/001457 mailed Dec. 13, 2011.
- Decision of Rejection for Japanese Patent Application No. 2007-211901, dated: Jan. 30, 2012.
